ATTORNEY.

UNITED STATES PATENT OFFICE

WILLIAM C. F. DIETZ, OF CINCINNATI, OHIO

SAFETY DISENGAGING MECHANISM FOR WRINGERS

Application filed March 11, 1926. Serial No. 94,023.

My invention relates to the broad class of safety disengaging mechanisms the particular adaptation disclosed herein being in combination with a power driven wringer, or 5 similar mechanism in which peripherally engaging rolls are employed.

It is the object of my invention to provide novel mounting means for engaging rollers in wringers of the type wherein one of the 10 rollers is usually power driven and another is driven either by frictional peripheral contact with the driven roll, or by independent gear elements. It is further my object to provide, in combination with the rollers, 15 devices disposed conveniently to the work feeding position which will with slight pressure automatically throw the rolls out of engagement, thereby eliminating much of the danger of the hands or other parts of 20 the body being caught between the rollers.

Specifically it is my object to provide in a power driven wringer in which clothes are fed through between independently mounted rollers a releasing plate disposed conveniently to the position in which the clothes are fed which is so constructed and so connected with the mounting for the engaging roller that even though both of the hands of the operator may be caught between the 25 rolls, pressure on the releasing plate with the arm or body will release or trip the mounting of one of the rollers so that it will move out of contact with the other, so that any parts of the body which are pinched 30 between the rollers may be withdrawn 35 without serious injury.

Furthermore, it is an important object of the present invention to so place the releasing plate that when the fingers or clothing 40 of the operator are accidentally caught between the rollers, the feeding action will necessarily bring the hand or body into operating engagement with the release plate 45 and effect the release of the parts caught without voluntary or direct effort on the part of the operator.

In the ensuing disclosures I have illustrated an embodiment of my invention in 50 combination with a power driven wringer,

in which there is a driven roll and a frictionally engaging roller.

Referring to the drawing:

Figure 1 is a front elevation of the roller mechanism in a power driven wringer. 55

Figure 2 is a side elevation of the parts illustrated in Figure 1.

Figure 3 is a front perspective view of my novel hand rest.

Figure 4 is a side perspective view of a 60 portion of the mechanism showing the tripping devices at the end of each of the friction rollers.

Figure 5 is a front elevation of the mounting bracket for the engaging roller. 65

Figure 6 is a section of the mounting bracket along the lines 6—6 in Figure 5.

Figure 7 is a perspective view of an end of the safety device showing the preferred type of tripping cam. 70

A wringer of the type illustrated comprises a stationary frame 1 in which a driven roller 2 is mounted. The actual drive for the driven roller is not shown as the particular type of drive forms no part of my invention. The drive may be by gears, belts, chains, or other well known mechanical constructions. The engaging roller 3 is mounted in an upper casing 4 the spindles 5 of the roller 3 being mounted in journal blocks 80 6 which are compressed downwardly by a spring 7 extending across the casing 4. A cam faced element 8 is journaled in the center of the casing 4 and extending from the cam element is a handle 9 by which the frictional engagement of the roller 3 may be regulated. Although I have illustrated a preferred type of wringer, it should be understood that I do not wish to limit myself to a wringer having an upper frictionally 85 engaging roller as the upper roller may be driven by a gear train operated independently or in conjunction with the driven roller.

A pair of releasing plates 10, pivotally 95 mounted by means of bosses 11 on the ends of the plates which engage pins 12 secured in the frame 1, are disposed in position preferably on each side of the rollers so that in feeding clothes between the rollers 100

the work or the hands may rest on the plates 10. The releasing plates in the embodiment illustrated may be used to serve a double duty of providing a suitable hand rest and also providing a simple safety device. It should be understood, however, that to provide a wringer with a hand rest is old and that my invention consists in the provision of a safety device which may be mounted entirely independently of the wringer hand rest, the only positive requirement being that the releasing plate be located conveniently to the work feeding position. While in the illustration I have shown a releasing plate on each side of the rollers the provision of a single releasing plate may in some cases be advisable.

In order to provide mechanism which will eliminate almost entirely all risk of the clothing or parts of the body becoming caught between the rollers I have provided a pair of releasing plates each of which in the embodiment illustrated constitutes a hand rest so that either will co-operate with the mounting of the engaging roller and will with slight pressure release the tension on the spring 7 so that the engaging roller will automatically spring out of engaging position.

Referring particularly to Figure 4 it will be noted that the casing 4 is secured to bifurcated spring clips 13 which have apertures 13^a in the bifurcated ends which are adapted to seat on pins 14 which extend from the lower housing 1. The releasing plates 10 have cam faced tripping lugs 16 extending from the bosses 11 which engage the ends of the spring clips so that when the releasing plate on one side is pushed downwardly the ends of the springs engaged by the cam lugs on that side of the wringer are disengaged and the spring 7 causes the casing 4 to swing on its engaged pivots which are the pins 14 on the other side of the housing 1.

Thus it will be obvious that should an operator or his clothing become entangled all that is necessary is to push on the releasing plate to effect a complete disengagement.

Furthermore, upon re-engagement of the spring clips with the pins 14, the cam lugs are pressed downwardly due to the strength of the spring action of the clips and the plates are automatically reset for releasing action.

Although I have shown but one embodiment of my invention, it will be understood that modifications can be made without departing from the principles involved.

Having thus described my invention, what I claim as new and desire to secure by Letters Patent, is:—

1. A clothes wringer comprising a stationary frame carrying a driven roller, a complementary frame mounted on the stationary

frame and carrying an engaging roller, a spring carried in the complementary frame for forcing the engaging roller toward the driven roller, locking means at each end of said spring for holding the complementary frame to the stationary frame against the tension of the spring, said locking means also serving as a pivotal connection between the two frames and permitting swinging action of the complementary frame to either side of the stationary frame. 70

2. A clothes wringer comprising a stationary frame carrying a driven roller, a complementary frame mounted on the stationary frame and carrying an engaging roller, a spring carried in the complementary frame for forcing the engaging roller toward the driven roller, locking means for holding the complementary frame to the stationary frame against tension of the spring, 80 said locking means also serving as a pivotal connection between the two frames permitting of the swinging action of the complementary frame to either side of the stationary frame, and means carried by the stationary frame for releasing the locking means. 85

3. A clothes wringer comprising a stationary frame carrying a driven roller, a complementary frame pivotally mounted on the stationary frame and carrying an engaging roller, a spring carried in the complementary frame for forcing the engaging roller towards the driven roller, means for locking the complementary frame against pivotal action on the stationary frame, 95 means mounted on the stationary frame for releasing the locking means, said locking means also serving as a pivotal connection between the two frames permitting the complementary frame to swing to either side of the stationary frame. 100

4. A clothes wringer having a driven roller and an engaging roller, a stationary frame carrying the driven roller and a complementary frame carrying the engaging roller, two pairs of pivotal connections between the stationary frame and the complementary frame, both pairs being detachable, and means lying adjacent the line of contact of the two rollers for detaching one pair of pivotal connections to permit pivotal action of the complementary frame about the other pair. 110

5. A clothes wringer having a driven roller and an engaging roller, a stationary frame carrying the driven roller and the complementary frame carrying the engaging roller, two pairs of detachable pivotal connections between the stationary frame and the complementary frame, a spring normally operating to press the engaging roller into contact with the driven roller but, 120

upon detaching one pair of pivotal connections, operating to cause pivotal action of the complementary frame on the other pair 125

130

of pivotal connections for releasing the pressure of the spring, and independent releasing means for each pair of pivotal connections for detaching a pair of said connections to permit pivotal action of the other pair.

6. A clothes wringer comprising complementary rollers capable of feeding clothes between them from either side of the wringer, separate frames carrying said rollers, two pairs of detachable, pivotal connections between the frames, one on each side of the wringer, means on each side of said wringer and adjacent the juncture of the rolls for releasing the pair of connections on the side from which the feeding is done to permit pivotal action of the frames on the opposite pair of pivotal connections, and means for automatically resetting the releasing means upon re-engagement of the pivotal connections.

7. A clothes wringer adapted to be power driven having a driven roller and an engaging roller resiliently held against said driven roller, separate frames for each of said rollers, a pair of detachable pivotal connections on each side of said frames, each of the connections having one resilient member normally holding said frames in fixed relation to each other, releasing means comprising a pair of plates, one on each side of and extending across the wringer substantially in alignment with the juncture of the rollers, pivotal connections on the ends of each of said plates to permit rocking action of said plates, means on the ends of said plates for disengaging one pair of pivotal connections of the frames when one plate is rocked and for disengaging the other pair when the other plate is rocked, a spring normally pressing the engaging roller against the driven roller, acting to cause pivotal action of the frames on one pair of pivotal connections when the other pair of connections has been disengaged by one of the releasing plates, the resiliency of the pivotal connection serving to automatically re-engage the disconnected pivotal connections when said connections are brought into alignment and to reset the releasing plates for releasing action.

WILLIAM C. F. DIETZ.
